ADJUSTABLE LIQUID METERING MEANS
FOR SHUT-OFF VALVES

James A. Kozel, Franklin, and Gerald L. McClure, Warren, Mich., assignors to American Radiator & Standard Sanitary Corporation, New York, N.Y., a corporation of Delaware

Filed Apr. 3, 1963, Ser. No. 270,442
5 Claims. (Cl. 137—613)

This invention relates to shut-off valves for liquid lines, and particularly to valves which are provided with adjustable metering means for regulating the volumetric flow when the shut-off element is in the open position.

One object of the present invention is to provide a shut-off valve with a metering means which will produce a wide range of flows, starting from substantially zero flow up to the full capacity of the valve.

A further object is to provide a metering means which holds its adjusted position in spite of widely varying liquid pressures.

An additional object is to provide a metering means which is easily accessible for adjustment purposes, which does not add appreciably to the size of the shut-off valve on which it is mounted, and which has a relatively low manufacturing cost.

Other objects of this invention will appear from the following description and appended claims, reference being had to the accompanying drawings forming a part of this specification wherein like reference characters designate corresponding parts in the several views.

In the drawings:

FIGURE 1 is a sectional view taken longitudinally through one embodiment of the invention;

FIG. 2 is a sectional view taken substantially on line 2—2 in FIG. 1;

FIG. 3 is a sectional view taken longitudinally through a second embodiment of the invention; and

FIG. 4 is a sectional view taken longitudinally through a further embodiment of the invention.

Before explaining the present invention in detail, it is to be understood that the invention is not limited in its application to the details of construction and arrangement of parts illustrated in the accompanying drawings, since the invention is capable of other embodiments and of being practiced or carried out in various ways. Also, it is to be understood that the phraseology and terminology employed herein is for the purpose of description and not of limitation.

FIGURE 1 CONSTRUCTION

In FIG. 1 there is shown a shut-off valve 10 comprising a valve housing 12 internally contoured to define a cylindrical entrance passage 14, an annular inlet chamber 16, a cylindrical outlet chamber 18 concentrically arranged inside of the inlet chamber, and a cylindrical exit passage 20 extending right angularly from the outlet chamber. The annular wall between chambers 16 and 18 forms an annular valve seat 22 which is located beneath the diaphragm type shut-off element 24.

In the illustrated construction element 24 has its outer peripheral edge area disposed beneath the peripheral flange 26 of the upright armature guide 28. Although not shown in the drawing, the armature guide extends upwardly a considerable distance to form a guide surface

2

for the plunger type armature 30 which is arranged above the central opening 32 in the diaphragm element. As is conventional, the armature is disposed within the interior of an electric solenoid 34 which is carried in a conventional C-shaped frame 36. Various mechanisms may be provided for retaining the frame and solenoid coil in position, but as shown in the illustrative drawing the coil-supporting frame 36 is provided with a downwardly struck arm 38 which has a foot portion suitably affixed to the mounting bracket 40, as by a screw, the head of which is partially visible in FIG. 1.

The mounting bracket 40 is suitably apertured and positioned on the upper face of housing 12 to overlie the flange 26 and thus retain the armature guide and diaphragm in place. Three or more screws, one of which is visible at 42, may be provided to fixedly retain bracket 40 on the valve housing.

In operation, energization of the solenoid 34 raises the armature 30 which allows liquid to be exhausted from the space above diaphragm 24 through the central opening 32 and thus permits the liquid pressure in chamber 16 to move the diaphragm upwardly from the illustrated position. When the solenoid is de-energized the armature 30 drops downwardly to close the opening 32 so that liquid can flow from chamber 16 through the small peripheral opening 44 and thus exert a closing force on the upper face of the diaphragm element.

The present invention is concerned particularly with a novel metering means for adjusting or regulating the volumetric flow past valve seat 22 when the diaphragm shut-off element is in its open position. As shown in FIG. 1, the metering means comprises a generally hollow tubular metering element 46 and a rotary metering element operator 48. The metering element comprises a cylindrical portion 50 extending into the lower portion of outlet chamber 18 and a longitudinally slotted portion 52 having rack-forming teeth 54 in meshing engagement with the pinion 56 which is formed as part of operator 48.

The operator is of generally shaft-like configuration and is provided with an enlarged central portion 58 which is seated in a cylindrical cavity in the upper face of housing 12, whereby the operator is mounted for rotary movement about a vertical axis. Formed in the cylindrical portion 58 is a peripheral groove which receives the O-ring sealing element 60. The upper portion of the metering element is of reduced diameter and extends through an opening in bracket 40 so that part of the bracket overlies cylindrical portion 58 to thus retain the operator in its installed position. For adjusting purposes the operator is provided with a screwdriver slot 62.

In operation of the FIG. 1 embodiment, the operator 48 may be manually rotated to cause the pinion 56 to move the tubular metering element 46 longitudinally back and forth to different adjusted positions in the exit passage 20. In its illustrated position the metering element completely blocks the flow of liquid from outlet chamber 18 into exit passage 20. Rotary movement of the operator 48 advances the metering element 46 rightward to allow increased flows through the metering element in accordance with the extent of rotary movement.

FIGURE 3 CONSTRUCTION

In the FIG. 3 embodiment the metering element comprises a cylindrical tubular member 46' having a trans-

verse slot 47 in its upper side surface for reception of a pin 64 which is eccentrically located on the metering element operator 48.

In operation of the FIG. 3 embodiment, manual rotation of operator 48 causes pin 64 to move in an arc around the operator axis to draw the metering element 46' rightwardly in accordance with the extent of operator rotation. Thus, the articulated connection provided by pin 64 functions to effect longitudinal movement of element 46' in much the same manner as the pinion 56 of the FIG. 1 embodiment.

FIGURE 4 CONSTRUCTION

In the FIG. 4 construction the metering element 46" is of generally tubular hollow configuration and is provided with gear teeth 54' on its rightmost peripheral end edge. Meshed with teeth 54' is the pinion 56 which constitutes part of the operator 48. In the FIG. 1 and FIG. 3 embodiments the metering element is mounted for longitudinal movement, whereas in the FIG. 4 embodiment the metering element is mounted for rotary movement within passage 20. The left end portion of the metering element is cut away, as at 66 for defining a regulator wall portion.

In the illustrated position of element 46" the cut away portion 66 faces upwardly so that chamber 18 liquid can pass into the interior of the metering element and thence through exit passage 20. Manual rotation of operator 48 causes metering element 46" to be rotated to turn the cut away portion 66 around the passage 20 axis, thus providing a range of flows through the valve housing. In a position rotated one-half revolution from that shown, the cut away portion 66 is completely shielded from the outlet chamber 18, and the metering element allows substantially zero flow through the valve.

FEATURES OF THE INVENTION

It will be noted that in each of the illustrated embodiments the metering element is a hollow tubular element having an internal diameter which is substantially the same as the diameter of chamber 18. Because of this the metering element can be adjusted to a full-flow position in which it contributes substantially no restriction to the liquid flow. Thus, the element in its fully open position has a capacity which approximates the full capacity of the shut-off valve.

It will also be noted that in each of the illustrated embodiments the fluid pressure in chamber 18 acts radially against the face of the metering element and also axially or peripherally. The radially acting forces do not tend to displace the metering element from any of its adjusted positions, and the only liquid pressure forces which have any element-displacing tendencies are those forces which act against the annular edge of the metering element. This annular edge in each case presents a minimal wall area to the fluid pressure so there is little tendency for displacement of the metering element, even when the fluid pressures are relatively high.

A further interesting feature of the illustrated embodiments resides in the construction and mounting of the metering element operator. Thus, the operator has a rotary movement, but no axial movement, so that it can be operatively mounted in a portion of the valve housing 12 which has no appreciable thickness. This is in contrast to the conventional needle-type metering elements which are arranged to move axially and which require a relatively thick wall portion for mounting and sealing purposes.

As a feature of further interest, it will be seen that the metering element operator is retained in place by the mounting bracket 40 for the valve housing, thus eliminating a separate retainer device for the operator.

Further, the metering element operator is in each case located in a position of easy accessibility from the area above the valve housing which is already by necessity clear for access to the solenoid terminals. Thus, during installation or service periods the terminals for the solenoid 34 and the operator 48 are each easily accessible from the same area. In certain household water supply arrangements a plurality of the illustrated valves may be positioned quite close to one another so that the feature of easy accessibility is quite important.

The invention has been illustrated in three embodiments but it will be appreciated that the invention is not restricted to the exact details of construction shown in the drawings, and that variations may be resorted to as come within the scope of the appended claims.

What is claimed:

1. In a solenoid controlled shut-off valve comprising a valve housing having a flanged armature guide mounted on one of its faces, and a bracket positioned over the flange to retain the guide in place: the improvement comprising adjustable flow metering means having an adjustment operator mounted in the housing beneath a portion of the bracket; said bracket having an opening therethrough, and said operator having a reduced diameter portion projecting through the bracket opening, whereby the bracket overlies the portion of the operator located within the housing to retain said operator in position.
2. In a shut-off valve comprising a housing forming a horizontally directed entrance passage, an annular inlet chamber connected with said entrance passage, an outlet chamber concentric with the inlet chamber and cooperating therewith in defining a valve seat, and an exit passage directed horizontally from the outlet chamber in alignment with the entrance passage; a diaphragm extending across the inlet and outlet chambers to control flow past the valve seat; means for controlling the diaphragm comprising an upstanding armature guide having a flange overlying the peripheral edge area of the diaphragm, a plunger type armature within the guide, and a solenoid surrounding the guide; and a bracket positioned on the upper face of the housing in overlying relation to the armature guide flange whereby to retain the guide and diaphragm in place: the improvement comprising a metering element disposed in the exit passage for movement across the outlet chamber; and a rotary upstanding operator for the metering element mounted in the uppermost wall of the housing and extending downwardly into the exit passage, said bracket overlying part of the operator to retain same in its mounted position; said operator being disposed in a portion of the housing located alongside the solenoid whereby the solenoid and operator are each accessible from above the valve housing; said metering element comprising a hollow thin-walled element engaging the exit passage surface for movement from a substantially fully closed position extending across the outlet chamber to a substantially fully open position approximating the full capacity of the shut-off valve.

3. The combination of claim 2 wherein the metering element is provided with a longitudinally extending rack portion, and the operator is provided with a pinion gear in meshing engagement therewith for effecting translational movement of the element.

4. The combination of claim 2 wherein the metering element is provided with a transverse slot, and the operator is provided with an eccentric pin engaged in said slot for effecting translational movement of the element.

5. The combination of claim 2 wherein the metering element is provided with peripheral teeth on one of its end edges, and the operator is provided with a pinion gear in meshing engagement therewith for effecting rotational movement of said element.
